UNITED STATES PATENT OFFICE.

SAMUEL HEIMBERG, OF CHELSEA, MASSACHUSETTS.

DESIGN FOR A WRIST-WATCH PROTECTOR.

52,271.

Specification for Design.

Patented Aug. 20, 1918.

Application filed February 2, 1918. Serial No. 215,210. Term of patent 3½ years.

To all whom it may concern:

Be it known that I, SAMUEL HEIMBERG, a subject of the Emperor of Austria, residing at Chelsea, in the county of Suffolk and State of Massachusetts, have invented a new, original, and ornamental Design for a Wrist-Watch Protector, of which the following is a specification, reference being had to the accompanying drawing, forming part thereof.

Figure 1 is a plan view of a wrist watch protector showing my new design, and Fig. 2 is an edge view.

I claim:

The ornamental design for a wrist watch protector as shown.

SAMUEL HEIMBERG.

Witnesses:

DAVID SCOTT,
ESTHER FRIEDERMAN.
